1

This invention relates to improvements in thermomagnetic generators and refrigerators, particularly such devices as are disclosed in applicant's copending applications Serial No. 627,832, filed November 10, 1945, now Patent No. 2,510,800, and Serial No. 635,980, filed December 19, 1945, now Patent No. 2,510,801, both relating to generators, and Serial No. 54,041, filed October 12, 1948, now Patent 2,589,775, dated March 18, 1952, and relating to refrigerators. In said applications there is described a particular constituent part referred to as "composite laminations" or a "composite section" occupying a gap in a magnetized armature and subjected to the action of a magnetic field the intensity of which varies with a designated frequency, for instance the frequency of a commercial alternating current. Said "composite" part itself is constituted by a plurality (or multitude) of ferromagnetic elements in the form of sections of laminae, plates, perforated plates, tubes, etc., having serially differing Curie point temperatures or having a progressive variation of Curie point temperatures, from one side to the other; these elements being so assembled that a number of ducts or passages are provided for the circulation of a liquid, or the oscillation of a liquid column (in a direction parallel to the progressive variation of Curie point temperatures) in the interstices between the elements, in order to effect alternating heat exchanges between the liquid and said ferromagnetic elements.

In the case of a thermomagnetic generator the alternating circulation of the liquid through the composite laminae produces their periodical heating and cooling in the region of Curie point temperatures, and an alternating current is induced in windings (coils) of the armature. In the case of the refrigerator an alternating current through the windings of the armature produces heating and cooling of the composite laminae by magnetization and demagnetization, and the circulation of the liquid serves to abduct the produced heat and cold.

A particularly important case is that where the liquid used is a metallic one, and most particularly is a molten alkaline metal or an alloy of alkaline metals, for instance of sodium and potassium. In this case some appreciable Foucault-current losses may occur in the "composite section," as well as in the metallic liquid passing through it.

In order to reduce to a minimum, or eliminate said Foucault-currents, it is provided, in accordance with the present invention, that the alter-

nating magnetic flux, coursing through the "composite section" part, shall be parallel to the alternating passage (through the same constituent part) of the metallic liquid; also that the said composite section shall be constituted of a number of ferromagnetic tubes (preferably flat) which are separated and insulated from each other and arranged, in the direction of length, parallel to the alternating magnetic field. Said tubes should be, on their outer portions, electrically insulated from each other, so as to prevent any induction, across the totality of these elements, by Foucault-currents, which are perpendicular to the magnetic flux.

These ferromagnetic elements, constituting the composite section, may, for instance, have the form of a sheaf (cluster) of tubes of ferromagnetic material, with the metallic liquid circulating, or oscillating lengthwise on the inside of these tubes, parallel to the magnetic flux. Or else, and preferably, very flat ferromagnetic tubes are used, said tubes being juxtaposed to each other and slightly insulated electrically between themselves, like the laminae of the armature of an electric transformer. In such case, the composite section will be very similar to the armature of an electric transformer, with the difference that the soft iron laminae are here replaced by hollow laminae (or flat tubes) made of a special ferromagnetic alloy, with, naturally, the essential peculiarity that the composition of the ferromagnetic alloy of each such tube (or such hollow laminae) will vary along the tube in a continuous or discontinuous manner from one end to the other, so that the Curie point temperature is highest at one end of the tubes, and lowest at the other end, and that, between these limits, the Curie point temperature varies gradually along these tubes from one end to the other in a continuous or discontinuous manner.

The tubular ends of these composite sections are lengthened, or extended, by tightly soldering or welding them to corresponding tubular clusters and/or chambers of non-magnetic material. The chambers at the top and bottom communicate by means of transverse ducts in such a manner as to form a closed circuit, wherein the oscillation (or circulation) of the liquid metallic column (filling the closed circuit) can take place.

In an important modification, the circuit is not closed but each of the two ends of the column is closed by means of a special device adapted to maintain the oscillation of the liquid column.

The composite section is subjected to the action of the variable magnetic field, suitably syn-

chronized with the circulation of the liquid, as explained in the cited applications.

A practical embodiment of the invention is shown in the accompanying drawings, given as an example only, and in which

Fig. 1 represents diagrammatically, in longitudinal section, the application of this improvement to the case of a magnetic refrigerator;

Fig. 2 represents a section along the line II-II of Fig. 1;

Fig. 3 represents, in transverse section, a detail modification of the hollow laminae;

Fig. 4 represents diagrammatically, in vertical section, a modified form of oscillation-maintaining means;

Fig. 5 represents diagrammatically, in plan view and partly in section, a modified form of generator;

Fig. 6 represents, in elevation and partly in section, the generator shown in Fig. 5;

Fig. 7 represents a detail section, showing one element in the composite section, taken on the line VII-VII of Fig. 6;

Fig. 8 represents a detail section showing a modified form of elements, corresponding to the element shown in Fig. 7;

Fig. 9 represents a detail elevation of the elements shown in Fig. 8, and

Fig. 10 represents a detail section showing another modified form of element, corresponding to the elements shown in Fig. 9.

Referring to Figs. 1 and 2, the composite sections 1, 1' comprise assemblies of flat tubes of suitable ferromagnetic alloys the composition of which varies from the lines *a*, *a'* to the lines *b*, *b'*, respectively, in such a way that there is a progressive decrease in Curie point temperatures along the length of said tubes; i. e., having the material with the maximum Curie point temperature adjacent the lines *a*, *a'* and that with the minimum such temperature adjacent the lines *b*, *b'*. The tubes comprising the sections 1, 1' are lengthened or extended at the "high" end by means of short tube assemblies 2, 2', and at the "low" end by means of similar tube assemblies 3, 3', the assemblies 2, 2', 3, 3' being of homogeneous magnetic material, such as soft iron, having a Curie point temperature appreciably higher than that of any part of the sections 1, 1'.

The tubes 2, 2' open into compartments or chambers 4, 4' the walls of which are preferably provided with generally annular external fins 5, 5' and with elongated internal fins 6, 6'; said fins serving to facilitate the transfer of heat from a fluid in the chambers 4, 4' to the ambient fluid around the fins 5, 5'. Beyond their finned portions the chambers 4, 4' are connected by a tube 7 (preferably of circular cross-section) having a thin wall of non-magnetic material, such as stainless steel, and within the tube 7 is located a slidable piston 8 adapted to oscillate freely lengthwise of the tube and made of a magnetic material. Around the tube 7 is placed a winding or coil 9, having connections for receiving an alternating current, and a ring 10 of magnetic material encasing the coil. The piston 8 is centered by means of springs 11, 11' which are attached to the walls of the chambers 4, 4'; as by means of the tension-adjusting screws 12, 12'.

The opposite ends of the tubes (3, 3') open into the chambers 13, 13' which are connected by a tube 14 of non-magnetic material, shown as being provided with internal and external fins.

The sections 1, 1'; extensions 2, 2' and 3, 3'; chambers 4, 4', 13, 13' and tubes 7 and 14 form

a closed circuit which is filled with a column of metallic liquid terminating on opposite ends of the piston 8, the natural frequency of oscillation of said column being regulated mechanically by adjusting the tension of the springs 11, 11' so that it will equal the frequency of the alternating current supplied to the coil 9. The piston 8, magnetically coupled to the coil 9 and ring 10, thus constitutes an electro-mechanical oscillator which assures maintenance of oscillations of the column at the frequency of the current supplied. A similar oscillator may be applied to the tube 14, if necessary, replacing all or part of the fins, but this is generally not desirable since this is the part of the system which absorbs heat at low temperature to cause the refrigerating effect, as described in application Serial No. 54,041.

In this apparatus the Curie effect results from the provision of a permanent magnet 15 having pole pieces (or shoes) 16, 17, with windings 18 thereon. The ends of the pole pieces are in communication with the tube assemblies 2, 2' and 3, 3', respectively, so that the magnetic flux is divided in two closed circuits, completed through the tube assemblies 1, 1', constituting composite sections with a progressive variation of Curie point temperatures, as described above. Alternating magnetizing and demagnetizing currents pass through the windings 18 (generally from the same source which supplies the coil 10) in such a manner that the magnetic flux of the magnet 15 is closed alternately in the circuit through section 1 and in the circuit through section 1', with said flux varying in intensity in said sections but keeping its sign unchanged. The flux in section 1 is dephased by 180° with respect to the flux in section 1' and the flow of metallic fluid through said sections is suitably synchronized in phase with the passage of the magnetic flux therein.

It is intended that the flat tubes constituting the sections 1, 1' should be insulated from each other by air-spaces or layers of insulating material 19, and the extensions of said tubes in the assemblies 2, 2', 3, 3' are likewise insulated from each other, in order to prevent the formation of Foucault-currents in said tubes or in the liquid flowing through them. The pole pieces 16, 17 are, naturally, also laminated for the same purpose.

In the modification shown in Fig. 3, any or all of the flat tubes in sections 1, 1' or the extensions thereof may be subdivided by providing a plurality of ribs, walls or spacers 19 running across the small dimension of the tubes and longitudinally thereof, so as to prevent deformation of the tubes by internal or external pressure.

The same system can readily be adapted for reducing the Foucault-currents in the case of the thermo-magnetic generators, utilizing metallic liquid, which are disclosed in applications Serial No. 627,832 and Serial No. 635,980. Preferably, however, when great differences of the Curie point temperatures between ends of the composite sections (for instance of several hundred degrees C.) are utilized, it is preferred to place the electro-mechanical oscillator in the cold tube of the generator. It is also necessary to separate the end of the permanent magnet or its pole pieces, adjacent to the hot ferromagnetic tubes, by an appropriate layer of a heat-proof thermal insulating material, in order that the corresponding pole of the magnet can be kept at a sufficiently low temperature, consistent with the preservation of its magnetic properties.

As an alternative, the permanent magnet may be replaced by an electro-magnet, through the winding of which flows a constant current, obtained, for instance, by the rectification of the alternating current normally supplied to the refrigerator, or generated by the generator.

The invention also comprises a method and means for maintaining the liquid metal column in oscillation, without utilizing any moving mechanical parts whatsoever, but solely by means of heat and of the alternating electric current.

In order to achieve this result, the electro-mechanical oscillator previously described (8, 9, 10, 11, 11', 12, 12' of Fig. 1) and the tube 7, are omitted. The two ends of the metallic liquid column are each provided with an electric superheater, wherein the said ends of the column are subjected, alternately, to successive superheating by the alternating phases of the rectified alternating electric current. Each such superheating produces instantly a mass of metallic vapors under pressure, which act alternately on the respective ends of the liquid column; the vapors at one end being condensed as the liquid at the other end is vaporized. The work performed by these vapors serves to maintain the oscillations of the column. This mechanism is represented in Fig. 4 (wherein the portion below the chambers 4, 4' is omitted, but may be similar to that shown in Figs. 1 and 2), the two superheaters, adjoining the "hot" chambers 4, 4' being formed by conical chambers 20, 20', with exterior fins 21, 21' and interior fins 22, 22', adapted to act as condensation chambers for the metallic vapors. The small ends of the chambers 20, 20' are in communication with the tubes 23, 23', respectively, which tubes have relatively thin walls of steel, with a very great specific electric resistivity.

Tubes 23, 23' are hermetically closed at the top and are preferably capped by metallic blocks 24, 24' for receiving the heavy electrodes for the rectified heating current. Annular blocks 25, 25' for receiving the opposite electrodes are located at the bottom of the tubes. Suitable thermal insulation 25, 25' may desirably be applied around the tubes 23, 23' and blocks 24, 24', 25, 25'. Thick walled metallic tubes 27, 27' may optionally surround and enclose the tubes 23, 23', said tubes 23, 27 and 23', 27' being insulated from each other by thin layers of electrical insulating material 28, 28', which also insulates tubes 27, 27' from the blocks 24, 24', 25, 25'. Consequently, the electric current passing through tubes 23, 23' and through the liquid metal column in said tubes, does not pass through the tubes 27, 27'.

Tubes 27, 27' are intended to form a solid support for tubes 23, 23', so that, because of such a support, said latter tubes may have very thin walls and can resist even a great internal pressure of the metallic vapors, while absorbing very little electric energy. The rectifying arrangement 29 and transformers 30, 30' receive the alternating current and transform it into direct current pulses of low voltage and high intensity which are sent alternately to the tubes 23 and 23'. A wall 31 preferably separates the area of the chambers 4, 4' from that of the superheaters and condensers of the metallic vapors.

In the case of the refrigerator, the primary current for the superheater is also the alternating current operating the refrigerator. In the case of the generator, the primary current may be the current produced by the generator itself.

The diameter of tubes 23, 23' should be large in relation to the thickness of the tubes' walls, in

order that the cross-section of the liquid metal in the tube will be much larger than that of said walls. Since the resistivity of the metal of the tube is chosen so as to be much greater than that of the liquid metal (for instance, potassium, sodium or their alloy), it is easy to provide that the resistance of the tube walls can be, for instance, at least several scores of times greater than that of the column of liquid metal and that almost the whole electric current shall pass through the metallic liquid, instantly superheating it above its boiling point temperature.

Thus each passage of the current through the column of liquid metal will produce instantaneous ebullition in the corresponding tube. Such a passage of the current is therefore immediately followed by formation of metallic vapors under pressure, which will push the column downward and will cause the liquid metal at the other end of the column to enter the other tube, and so on, with the metallic vapor being each time condensed in the condensers 20 or 20' which are maintained at an appropriate temperature by suitable means.

This mechanism can be used for both the refrigerator and the generator. The superheating must be sufficiently great to produce pressures of the metallic vapor, which will cause the mass of the liquid column to form an oscillating liquid metallic circuit having a frequency approximating the frequency of the electric current.

Generally comparable arrangements for assuring the oscillation of the liquid column having been described and shown in the copending application of November 10, 1945, Serial No. 627,832, now Patent No. 2,510,800, (Figs. 11, 12, 13 and particularly 14). The mechanism described in the present invention has an advantage over that shown in said Fig. 14, in that the tubes, wherein occur the instantaneous superheating and ebullition of the metallic liquid, are all metal (for instance, of highly resistant steel) and that any contact of the hot alkaline metal with any heat-proof material is entirely avoided. This eliminates the possibility of any chemical action between the hot alkaline metal and the heat-proof material and permits the use of higher superheating temperatures of the liquid metal and its vapor.

The result, in accordance with the present invention, is that each phase of the rectified alternating current, passing through the end of the liquid column, produces practically instantaneous superheating and ebullition of the metallic liquid, and thus the frequency of oscillation of the liquid column is definitely fixed by the frequency of the electric current, without necessarily having resort to the oscillation of any mechanical parts whatsoever, even auxiliary ones (piston, spring, etc.). This is true both in the case of the generator, and of the refrigerator.

In the case of the generator, it is obviously possible to use, for the heating and ebullition of the ends of the liquid columns, the rectified and transformed electric current of a comparatively weak independent source of alternating current, thereby eliminating any moving parts in the generator itself.

It is likewise possible to obtain any desired definite frequency by any other mechanical or electric means, merely by sending current impulses of the desired frequency for the heating of the metallic liquid in tubes 23, 23'.

Although the thermomagnetic oscillator, represented in Fig. 4 communicates to the parts ac-

tuated by it, i.e., to the liquid column, the frequency of the electric current passing through the said oscillator, it may be useful, in certain cases, to combine in the same apparatus, both the thermomagnetic oscillator (Fig. 4) and the electromagnetic oscillator (Fig. 1).

Sufficient space must be left in the closed circuit (tubes 23, 23' and, possibly, chambers 20, 20'), above the liquid metal, to make possible the oscillations of the column. This space may be 10 evacuated or may possibly be filled with an inert gas under pressure (for instance, helium, argon, neon).

In a modification, not shown on the drawing, said free space may be provided in two terminal bulbs attached to the upper parts of the tubes 23, 23'. Said terminal bulbs, generally of metal, may also form the condensers for the metallic vapor, and can be equipped, both on the inside and the outside, with appropriate ribs. In such case, the fins 21, 21', 22, 22' can be dispensed with. The said bulbs can, if desired, be filled with inert gas under pressure, forming, with the liquid column, a system possessing a suitable desired natural frequency of mechanical oscillations.

The start of operation of the system can be effected, for instance, by making the apparatus dissymmetric, or possessing an inclination in such a manner that the liquid, filling one of the tubes 23 or 23' shall, when at rest, touch the upper electrode.

In a modification, shown diagrammatically in Figs. 5 and 6, the magnetic circuit, comprising the permanent magnet, the pole pieces or armatures and the composite sections, on the one hand, and the closed circuits for the circulation or oscillation of the metallic liquid, on the other hand, are located in planes that are perpendicular to each other.

In Fig. 5 there is shown, in plan view and partly in section, the magnetic circuit consisting of the magnet 32, the armatures 33, and the composite sections interposed between opposite ends of the respective armatures and formed by flattened tubes 35, each tube being made, for instance, by welding together the opposite edges of two pieces of sheet metal, having a space 36 between them for the circulation of the metallic liquid. Adjacent tubes are insulated from each other, for instance, by thin layers 37 of oxide or any other appropriate insulating material, in order to prevent Foucault-currents from passing through the composite body.

The tubes 35 may be contained in the chamber, the walls 38 of which (adjacent armatures 33) are preferably made of magnetic material, while the lateral walls are of non-magnetic metal, so as to avoid a parasitic passage of the magnetic flux. These walls have for their purpose to resist the deformation of the tubes by internal pressure and they may be subdivided, as shown in Fig. 6, into bands or strips 39, either ribbed or plain.

Fig. 7 shows one of the tubes 35 (seen from the side); its walls have, at one end, a maximum Curie point temperature of T_n , and at the other end the minimum Curie point temperature of T_1 . The directions of flow of the metallic liquid are indicated by arrows (Fig. 6). The tube's wall is formed by multiple bands which are juxtaposed and welded together at the edges, each successive band having its own Curie point temperature, and said temperatures rising progressively and filling the interval of temperatures between T_1 and T_n . Or else, the walls may have, from

one end to the other, a continuous variation of Curie point temperatures, corresponding to a continuous variation of the percentage of the non-magnetic ingredient in the corresponding alloy. 5 (Said alternative constructions are fully disclosed in copending application Serial No. 635,988.)

Fig. 6 shows an elevation and sectional view perpendicular to the plane of Fig. 5 thus representing, in part, a section across the closed circuit of circulation, or oscillation, of the metallic liquid.

The passages 36 of the tubes 35 (intended for the circulation of the metallic liquid) open downwardly (preferably the lower temperature part) 15 into the collecting chamber 40, equipped with internal fins 41 and external fins 42 to facilitate the thermal exchanges. The two opposite collecting chambers 40, 40 are connected by a tube 43 containing a piston arrangement and electromagnetic operating means (not shown) of the same type as shown in Fig. 1, for causing the metallic-liquid column to oscillate.

At their upper ends the tubes 35 communicate individually with similar tubes 44 (outside the 25 composite sections) which, in turn, connect with corresponding tubes in the opposite composite section. The tubes 35 are electrically insulated from each other by insulating layers 37, while spaces 46 are left between the adjoining tubes 44 for the circulation of a hot, or cold, fluid between the tubes. The walls of the tubes 44 are made of homogeneous metal, which is preferably non-magnetic (so as to avoid the parasitic deviation of the magnetic flux).

35 The individual tubes 44 are sufficiently spaced apart so as to leave, in the interstices 46 between them, room for the circulation of an appropriate fluid which will insure the supply of heat (or the removal of heat, as may be required) to (or from) 40 the metallic liquid, circulating inside these tubes. The means insuring this circulation of the fluid between the said tubes, outside the composite sections, are not shown on the drawing.

35 The tubes 44 can be separated by supports indicated at 47 in Fig. 6, and appropriately placed in the spaces 46. An exterior wall or casing 48, similar to walls 39 and constituting, if desired, the prolongation of said walls, may be extended over the tubes 44. The supports 47 and the exterior 50 wall 48 have the purpose to resist the deformation of the tubes by internal pressure. Also, if necessary, the walls of the tubes 44, not being submitted to rapid alteration of temperatures, may have essentially thicker walls than the tubes 35.

The supports 47 must be insulated from the tubes 44 by a thin layer of insulating material, for instance, a layer of oxide, in order to oppose the passage of Foucault-currents, or these supports may be of insulating material, as shown.

Modified forms of tubes are shown in Figs. 8, 9 and 10, in which each flattened tube is replaced by a range of several (or of a multitude of) square or round tubes, juxtaposed and preferably welded together along their length, the adjacent ranges of these tubes being electrically separated or insulated from each other.

Fig. 8 shows two such parallel juxtaposed vertical ranges of tubes 49, forming a "composite body," these vertical ranges being insulated from each other by layers of insulating material 50. Such tubular ranges may be substituted for the tubes 35 of Figs. 5 to 7.

Fig. 9 shows a detail elevation of one of the ranges 49 of Fig. 8, and indicates the increasing Curie point temperatures, $T_1 \dots T_n$.

Fig. 10 shows a variation in which the tubular ranges are made of two undulated metallic sheets 51, provided with ribs 52, and being welded together through these ribs, in order to resist the interior pressure.

When the tubular ranges of Figs. 8, 9 and 10 are substituted for the flat tubes 35 in the composite sections the separate tubes of each range may be merged upwardly into the flat tubes such as tubes 44 and downwardly may open into chambers 40 as shown in Fig. 6. Alternatively, the wide flat tubes 35 may be merged upwardly into subdivided tubes (replacing the tubes 44) formed substantially in accordance with Fig. 10 or ranges of tubes as in Figs. 8 and 9.

As the tubes 44 or corresponding tubular ranges may have different lengths, it is provided to compensate these differences by corresponding differences in the interior cross-sections of the composing tubes, in order to equalize the dynamic and frictional resistance for the liquid in different tubes or ranges.

The tubes 35 or ranges 40 or 51, the walls of which comprise "composite laminae," having, one end to the other, progressively varying Curie point temperatures, may be called "active." Their extension, in the form of tubes 44, of homogeneous metal, may be called "passive." The role of the passive parts is to insure thermal exchanges for the liquid metal which these tubes contain, such exchanges being effected without uniting the separate small streams of liquid metal in a collecting chamber, where Foucault-currents could form. This dissymmetry in the closed circuit of the circulation of the liquid metal is essential for the reduction of Foucault-currents. Said dissymmetry consists in the fact that at one end of the two "composite sections" there are located the passive tubes, separated from each other (so that, consequently, no Foucault-currents can be generated), and at the other end there are located the collecting chambers for the metallic liquid. It is due to this separation from each other of the adjoining tubes—active or passive—that the electromotive forces induced in the collecting chambers of the metallic liquid are of opposite sign and neutralize each other.

Obviously, the collecting tube 43, with its piston-equipped device for maintaining the liquid column in oscillation, may be replaced by the actuating device shown in Fig. 4 for maintaining the oscillation of the liquid column. If desired, in order further to reduce the Foucault-currents, the oscillating liquid column may be divided into several juxtaposed parallel columns, by substituting separate passive tubes for the chambers 40, 40 and tube 43, each such tube having its own means (of any suitable kind) for maintaining oscillations.

What I claim is:

1. In a thermomagnetic apparatus having a polarized armature in a gap of which is located a composite section of ferromagnetic elements with different Curie points arranged across the section in regular order of Curie point temperatures and adapted to be heated and cooled in the neighborhood of said temperatures by the passage of fluid heating and cooling means; means for effectively reducing the formation of Foucault-currents comprising, hollow tubular ferromag-

netic elements constituting said section and adapted to conduct said heating and cooling means in the direction of variation of Curie points, and means for insulating said elements from each other.

2. Means according to claim 1 in which said elements are substantially flat tubes.

3. Means according to claim 1 in which the direction of variation of Curie points corresponds to the direction of magnetic flux in the section.

4. Means according to claim 1 in which said elements are substantially flat tubes subdivided internally by one or more walls extending in the direction of variation of Curie points and in which said direction corresponds to the direction of magnetic flux in the section.

5. Means according to claim 1 which includes electromechanical means for oscillating the heating and cooling fluid through the composite section.

6. Means according to claim 1 in which the armature is bifurcated and in which there are composite sections located symmetrically in each branch of the armature.

7. Means according to claim 6 in which said elements are substantially flat tubes.

8. Means according to claim 6 in which the direction of variation of Curie points corresponds to the direction of magnetic flux in the sections.

9. Means according to claim 6 in which said elements are substantially flat tubes subdivided internally by one or more walls extending in the direction of variation of Curie points and in which said direction corresponds to the direction of magnetic flux in the sections.

10. Means according to claim 6 which includes electromechanical means for oscillating the heating and cooling fluid through the composite sections.

11. Means according to claim 6 in which the direction of variation of Curie points is transverse to the direction of magnetic flux in the sections.

12. Means according to claim 11 in which said elements are substantially flat tubes.

13. Means according to claim 11 in which said elements are substantially flat tubes and in which separate insulated tubes connect the elements in one branch of the armature with respective elements in the other branch thereof.

14. Means according to claim 11 in which said elements are substantially flat tubes subdivided internally by walls extending across the short dimension thereof and lying in planes parallel to the direction of variation of Curie points.

15. Means according to claim 11 in which said elements are substantially flat tubes, each said tube being constituted by a range of juxtaposed small individual tubes and adjacent ranges being insulated from each other.
